UNITED STATES PATENT OFFICE.

AXEL N. MILLER, OF HARVEY, ILLINOIS.

SCAFFOLD.

1,360,131.

Specification of Letters Patent. Patented Nov. 23, 1920.

Application filed March 28, 1916. Serial No. 87,225.

To all whom it may concern:

Be it known that I, AXEL N. MILLER, a subject of the King of Norway, who have declared my intention of becoming a citizen 5 of the United States, and a resident of Harvey, county of Cook, and State of Illinois, have invented certain new and useful Improvements in Scaffolds, of which the following is a specification.

10 My invention relates to improvements in scaffolds and has for its object the provision of an improved scaffold construction which is readily demountable and readily re-assembled.

15 The invention consists in the combinations and arrangements of parts hereinafter described and claimed.

The invention will be best understood by reference to the accompanying drawings 20 forming a part of this specification, and in which,

Figure 1 is a side view of a construction embodying my invention,

Fig. 2, a view taken at right angles to Fig. 1, with portions broken away for the sake of clearness,

Fig. 3, a horizontal section of the construction,

Fig. 4, an enlarged section taken on line 30 4-4 of Fig. 1,

Fig. 5, a vertical section of one of a plurality of pulley blocks employed in the construction, and

Fig. 6, an elevation taken at right angles 35 to Fig. 5.

The preferred form of construction, as illustrated in the drawings, comprises a main frame made up of a suitable base of any desired construction and four hollow 40 upright guide posts at the corners thereof. Each of the guide posts is formed of two oppositely disposed channel beams 7 and 8 secured together, as indicated, the four posts being bound together and reinforced by 45 horizontal tie members 9 and diagonal tie members 10 to constitute a main supporting frame for the construction. A pulley block 11 is slidably arranged in each of the corner posts of the main frame and carries at 50 its lower end a grooved pulley 12, as indicated. Sockets 13 are provided at the upper ends of pulley blocks 11 and have notches

14 at their inner sides adapted to receive and accommodate cross beams 15, as shown. A plurality of cables 16 having their ends 17 anchored at the upper ends of the guide posts, are passed under pulleys 12 and over guide pulleys 18 and 19 to drums 20 arranged at each side of the machine. Each of the drums 20 is operatively connected by 60 means of a gear 21 with a gear 22 fixed to an operating shaft 23 and provided with a crank handle 24 for rotating the same. An ordinary pawl and ratchet 25 are provided for preventing retrograde movements of 65 shaft 23. By this arrangement, the cross beams 15 may be readily elevated or lowered in the main frame of the construction, as will be readily understood.

Corner members 26 having both upwardly 70 and downwardly opening tapering sockets 27 and 28 respectively, are provided for making up the scaffold frame sections, corner uprights 29 and 30 being correspondingly tapered at their ends to fit said sockets, 75 as best indicated in Fig. 4. The socket members 26 are provided with inwardly extending lugs 31 connected by means of horizontal tie members 32 and diagonal tie members 33 with each other so as to complete a rigid 80 scaffold section.

A locking dog 34 is provided in each of the guide posts of the main frame and operates through notches 35 provided in the sides thereof, said locking dogs being 85 adapted to project through said notches to automatically engage under socket members 26 resting on cross beams 15 when said beams are elevated, suitable notches 36 being provided in said beams to permit of 90 such engagement. The locking dogs 34 are arranged in pairs on shafts 37 connected together by means of a connecting link 38 so as to compel simultaneous operation of said dogs, as will be readily understood. 95

In use, to commence the building of the scaffold, the I beams are lowered in the main frame and four socket members 26 are placed thereon at the four corners of said frame as indicated. Uprights 29 are seated 100 in these socket members and similar socket members placed over the upper ends thereof, all of the socket members being bound together by the tie members 32 and 33, as in-

dicated, thus completing a scaffold frame section. Then this section is elevated by means of crank handle 24 until the lowermost socket members pass the dogs 34 which automatically engage thereunder to prevent return movement thereof. Then the beams 15 are lowered and new corner members 26 placed thereon as before. Uprights 29 are fitted in the upper sockets in these new corner members and in the lower sockets in the lower elevated corner members and tie members 32 and 33 secured in place as before, thus completing a new scaffold frame section. This scaffold frame section is elevated as before and a new section applied to the bottom thereof as before to increase the height thereof. Obviously this process may be continued until the desired height of scaffold is attained.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. The combination of a main frame; a scaffold frame support on said main frame; a plurality of scaffold frame sections adapted to be mounted on said support; means on said main frame for securing said scaffold frame sections in elevated positions; and means for elevating said support to elevate said scaffold frame sections successively and lowering said support independently of said scaffold frame sections to permit of the interposition of a scaffold frame section under an elevated scaffold frame section, substantially as described.

2. The combination of a main frame; a scaffold frame support on said main frame; a plurality of scaffold frame sections adapted to be mounted on said support and having provisions for securing both upwardly and downwardly extending scaffold frame members thereto; means on said main frame for securing said scaffold frame sections in elevated positions; and means for elevating said support to elevate said scaffold frame sections successively and lowering said support independently of said scaffold frame sections to permit of the interposition of a scaffold frame section under an elevated scaffold frame section, substantially as described.

3. The combination of a main frame; a scaffold frame support on said main frame; scaffold frame corner members adapted to be mounted on said support; means on said

main frame for securing scaffold frame sections in elevated positions; and means for elevating said support operable to elevate said scaffold frame sections successively and to lower said support independently of said scaffold frame sections to permit of the interposition of a scaffold frame section under an elevated scaffold frame section, substantially as described.

4. The combination of a main frame; a scaffold frame on said main frame; scaffold frame corner members adapted to be mounted on said support and having provision for securing both upwardly and downwardly extending scaffold frame members thereto; means on said main frame for securing said scaffold frame corner members in elevated positions; and means operable for elevating said support to elevate said scaffold frame sections successively and lowering said support independently of such scaffold frame corner members to permit of the interposition of a scaffold frame section under an elevated scaffold frame section, substantially as described.

5. The combination with a main frame; a scaffold frame support on said main frame; a plurality of scaffold frame sections adapted to be mounted on said support and having both upwardly and downwardly opening tapering sockets; means on said main frame for securing said scaffold frame sections in elevated positions; and means operable for elevating said support to elevate said scaffold frame sections successively and lowering said support independently of such scaffold frame sections to permit of the interposition of a scaffold frame section under an elevated scaffold frame section, substantially as described.

6. The combination of a main frame; a scaffold frame support on said main frame; scaffold frame corner members adapted to be mounted on said support and having both upwardly and downwardly tapering sockets; means on said main frame for securing said scaffold frame corner members in elevated positions; and means operable for elevating said support to elevate said scaffold frame corner members and lowering said support independently of said scaffold frame corner members to permit of the interposition of a scaffold frame section under an elevated scaffold frame section, substantially as described.

7. The combination of a main frame having hollow corner guide posts; pulley blocks slidable in said guide posts; cables arranged to elevate said pulley blocks; means for simultaneously and uniformly elevating all of said pulley blocks; cross beams resting on said pulley blocks; corner members having upwardly and downwardly opening sockets resting on said cross beams at the corners of said frame; upright corner members to fit

said sockets; tie members connecting said socket members to constitute a scaffold frame section, and means independent of the elevating means to engage and sustain the corner members when the elevating means are withdrawn, substantially as described.

5 In testimony whereof I have signed my

name to this specification in the presence of two subscribing witnesses.

AXEL N. MILLER.
